UNITED STATES PATENT OFFICE.

JOSEPH W. TROTTER, OF BIRMINGHAM, ALABAMA.

RAIL-JOINT.

1,299,393.

Specification of Letters Patent.

Patented Apr. 1, 1919.

Application filed December 28, 1918. Serial No. 268,051

To all whom it may concern:

Be it known that I, JOSEPH W. TROTTER, a citizen of the United States of America, residing at Birmingham, in the county of Jefferson and State of Alabama, have invented 5 certain new and useful Improvements in Rail-Joints, of which the following is a specification.

This invention relates to rail joints and 10 one of the principal objects of the same is to provide efficient and reliable means for joining the meeting ends of a pair of railroad rails and to permit the same to expand and contract without interfering with the 15 efficiency of the joint.

Another object is to provide a novel and effective means for anchoring the joint to the cross ties.

A further object of the invention is to 20 provide suitable spiral springs to fit on the bolts between washers so as to permit of a slight yielding action to the rail and joint.

Still another object is to provide a base lock bar to hold the joint sections from 25 spreading in case the bolts become loose.

Still another object is to provide a reinforcing web on each side of the joint preferably in the center between the supporting cross ties and opposite the joint in the track 30 rails so as to render the joint as strong as any part of the rail and as rigid.

Still another object is to provide interlocking elements in the bases of the joint sections so as to hold the joint sections 35 against relative longitudinal movement when the rails are expanding and contracting.

Still another object is to provide holes through the meeting edges of the bases of the joint sections and to pass tie bolts down 40 through these holes and secure them to brackets which engage under and between the adjacent cross ties.

My invention further comprises the novel 45 details of construction and arrangements of parts, which in their preferred embodiments only are illustrated in the accompanying drawings which form a part of this specification, and in which:

Figure 1 is a side elevation of my joint 50 in operating position.

Fig. 2 is a sectional view taken on the line 2—2 of Fig. 1, omitting the showing of the cross tie.

Fig. 3 is a bottom plan view of the joint proper with the tie bolts removed. 55

Fig. 4 is a sectional view taken on the line 3—3 of Fig. 1.

Fig. 5 is an end elevation of Fig. 1 omitting the tie engaging bracket.

Similar reference numerals refer to similar parts throughout the drawings. 60

I have illustrated my invention as applied to the meeting ends of track rails 1 and 2 which are provided with the customary bolt holes 3 and are seated in the rail joint 65 formed by two longitudinal half sections 4, which when assembled are shaped to provide between them a recess conforming to the base and web of the rail so as to fit the latter snugly and to engage under the head of 70 the rail in the manner well understood in this art. The bases 5 of the joint sections extend laterally beyond the base of the rails and are there provided each with a raised integral reinforcing web 15 in the center of 75 the joint and with openings 18 for the securing spikes. Bolts 6 are passed through the holes 3 in the web of the rails and through alining openings in the joint members and on each side of the joint I provide 80 a spiral spring 7 surrounding the bolt and interposed between a pair of washers 8, thus forming a yielding spring connection on each side of the joint. A nut 9 is screwed on the bolt 6 and held against displacement 85 by a cotter key 10.

In order to provide an additional means for more positively and rigidly securing the joint to the cross ties 12 in certain positions of the track which are subjected to abnormal strains, or where an accident would be of most serious consequences, such as on curves, bridges, etc., I provide a pair of tie bolts 11 which are passed through holes 21 90 formed partly in each of the meeting edges 95 of the joint bases 5 and the heads of the bolts are seated in countersunk recesses so as to lie flush with the interior bottom surface of the joint. These tie bolts are disposed to come between the adjacent pair of 100

ties and at their lower ends are passed through a metallic bracket member 17, the ends of which are adapted to engage under the cross ties and the middle portion of which is bent upwardly at right angles to form a spacing brace between the ties, thus bringing it above the ground level so as to expose the nuts 13 which secure the tie bolts 11 to the bracket. The rail web engaging portions of the joint members are reinforced by integral enlargements or shoulders 14 which extend from engagement with the head of the rail to the rail base engaging portions of the joint members, as will be seen more clearly in Fig. 4, where it will also be noted that the reinforcing webs 15 are in transverse alignment with the shoulders 14 and the rail joints, thus giving the joint its maximum strength where it is subjected to the greatest strain. Preferably the webs 15 have sloping ends to avoid engaging any hanging part of the train.

In order to insure the joint sections against separation should the securing bolts be broken or removed, I provide a tie bar 16 having up-turned end flanges which overlap the side edges of the joint bases 5, being slipped endwise thereon to hold them securely against separation. To hold the joint sections against longitudinal displacement as a result of the expansion and contraction of the rail, I provide one section with a lug or projection 20 which is adapted to fit into a correspondingly shaped recess 20^a in the opposite section. Preferably the lug and recess are tapered to center the joint members and bring their bolt holes into proper alignment.

To further insure the joint against lateral or spreading movement on the cross ties should the spikes work loose, I provide round iron studs 23 which are driven into the top surface of the ties so as to leave about one-half inch of their heads projecting and I provide the base of the joint members with sockets 19 adapted to receive these studs. I thus provide a loose fastening which underlies the rails and will hold them against spreading or lateral displacement, even after the spikes are removed.

In operation, having by measurements properly located and driven the studs 23 in the ties, the joint sections are assembled about the meeting ends of the rails and the tie bar 16 is slipped in place, which will hold the sections together and they will be centered by the lugs 20. After causing the studs to engage in holes 19 by shifting the ties, the spikes are driven and the bolts 6 inserted. Where it is necessary to use them, the tie bolts 11 are inserted between the joint sections when they are assembled and the bracket 17 is placed under and between the adjoining ties and the bolts 11 made fast thereto, thus completing the mounting

of the joint. When thus mounted and assembled the joint holds the tracks against spreading by the customary action of the spikes, and also by the studs 23, bolts 11 and brackets 17, which latter members rigidly resist any upward displacement of the joint should the spikes give way. The tie bar 16 being located between the tie bolts 11, makes it impossible to separate the joint plate even in a deliberate attempt to wreck a train, due to the fact that the bolts 11 cannot be withdrawn and the tie bar is thus held in place and cannot be slipped endwise off the joint, and in like manner even if the lugs 20 were omitted these bolts would serve to tie the joint members against endwise displacement. Moreover the lock bar works opposite the track joint and serves to rigidly hold together the joint members so as to keep the meeting ends of the rails in true alignment and prevent any relative displacement thereof which might occur otherwise when the bolts 6 work loose and cause a wreck. The reinforcement of the tie plate by the shoulders 14 under the rail joint, and also by the webs 15 even though the joints be spaced between ties, will give it the full strength needed to hold the rail tread surfaces in the same plane so as to avoid wearing the rail ends and flattening the wheels.

This invention is not intended to be restricted in scope to the specific embodiments shown, but contemplates such modifications as come within the spirit and scope of the claims.

Having thus described my invention, what I claim as new and desire to secure by Letters Patent, is:—

1. A rail joint formed in longitudinal half sections, a tie bar slipped endwise on and adapted to lock said sections together, and means to make the sections fast to the cross ties on each side of said tie bar, comprising a bracket engaging under the ties and tie bolts connecting the joint to the bracket.

2. A rail joint formed in longitudinal half sections, a tie bar slipped endwise on and adapted to lock said sections together, means to make the sections fast to the cross ties on each side of said tie bar, said means comprising a bracket engaging under the ties, and tie bolts connecting the joint to the bracket and arranged on each side of the tie bar.

3. A rail joint formed of longitudinal half sections shaped to fit snugly against the webs and about the bases of the rails, there being bolt holes formed in part in the meeting edges of the bases of both joint sections, tie bolts which pass through said holes, and means to make said tie bolts fast to the ties, substantially as described.

4. A rail joint formed in longitudinal half sections shaped to fit snugly about and under the web and base of the rail, the meeting

edges of the bases of said sections being notched to form a hole having a countersunk recess, tie bolts passing through said hole and having their heads seated in said countersunk recess, an angled bracket engaging under and between the adjacent pair of ties, and means to secure said tie bolts to the

raised intermediate portion of the bracket, substantially as described.

In testimony whereof I affix my signature. 10

JOSEPH W. TROTTER.
